UNITED STATES PATENT OFFICE.

PETER F. AUGENBRAUN, OF STAMFORD, CONNECTICUT, ASSIGNOR TO THE YALE & TOWNE MANUFACTURING COMPANY, OF STAMFORD, CONNECTICUT.

AUTOMOBILE-DOOR LOCK.

Application filed June 30, 1922. Serial No. 572,004.

To all whom it may concern:

Be it known that I, PETER F. AUGENBRAUN, a citizen of the United States, and a resident of Stamford, in the county of Fairfield and State of Connecticut, have invented certain new and useful Improvements in Automobile Door Locks; and I do hereby declare the following to be a full, clear, and exact description of the invention, such as will enable others skilled in the art to which it appertains to make and use the same.

My invention relates to an improvement in locks designed more particularly for use on automobile doors, the object being to provide a bolt deadlocking device with actuating means which do not depend upon the construction of the lock for its support, and which can be used in any position required by simply boring a hole in the door at the desired point, and it consists in the parts and combination of parts as will be more fully described and pointed out in the claims.

In the accompanying drawings, Figure 1 is a view of a lock embodying my invention. Figure 2 is a view in section through the door and frame and showing the preferred means for locking the cylinder of the pin tumbler lock in place. Figure 3 is a view in edge elevation partly in section of the door, showing the pin tumbler lock and its securing means and also the connecting bar which actuates the dead locking means. Figure 4 is a view in section on the line 4—4 of Figure 2. Figure 5 is a view in section of a modified form of cylinder securing means. Figure 6 is a view similar to Figure 2 showing the means shown in Figure 5 for locking the cylinder in place. Figure 7 is a view in section on the line 7—7 of Figure 6. Figure 8 is a view in edge elevation of a door embodying the construction shown in Figure 6. Figure 9 is a view in front elevation of the pin tumbler lock. Figure 10 is a view in section showing the connection between the plug of the pin tumbler lock and the connecting bar. Figure 11 is a view of the lock and its connecting bar in elevation. Figure 12 is a view similar to Figure 1 of a modification, and Figure 13 is a sectional view, wherein the cup shaped end 36^a of the screw 36 is illustrated.

15 represents a lock case designed more particularly for automobile doors, and 16 is

the bolt yieldingly forced into locking position by the spring 17, and retracted by the inside lever 18 which bears against the upwardly extending lug 19 on the bolt 16, the lever being yieldingly held away from the lug 19 by the spring 20.

The lever 18 is at the inner side of the door, and when the window of the door is closed, is accessible only from the inner side of the car.

The bolt 16 is mounted in or on the case 15 which is designed to be secured to the door 21 in the usual and well known manner, and engages a keeper carried by the side 22 of the body of the car, and is provided with a depending projection 23 adapted to be engaged by the roll back 24 secured to the hub 25 of the outside lever handle 26. The lug 23 on the bolt is normally held in contact with the roll back 24 by the spring 17, and the rollback 24 is actuated by the handle 26 to retract the bolt 16 from the outer side of the car.

Secured to the latch case is a dead locking mechanism consisting of a dead locking dog 27, a pitman 28 a pin tumbler lock and a connection between the plug of the pin tumbler lock and the pitman 28 for shifting the dog 27 to a position to engage or release the shoulder 30 on the roll back 24. When the dog is in contact with said shoulder, as shown in Figures 1 and 12, the outside handle is absolutely dead locked, consequently the bolt can only be retracted by the inside lever 18. When the dog is moved out of the path of shoulder 30 by the means to be hereinafter described, the bolt 16 may be retracted from the inside of the car by the lever 18, or from the outside by the lever handle 26.

Secured to the lock case 15 is the plate 31 which, as shown in Figure 1, is designed for a large lock, and the pin tumbler lock 32 is located near the edge of the door as shown in Figures 2, 6, 5, 7 and 8, and when so located is secured by a screw 36 mounted in a sleeve 33 secured within a hole in the inner edge of the door. The sleeve shown in Figure 2 is provided with one or more peripheral ribs 34 which are provided with milled or knurled peripheries adapted when forced into the hole in the door, to engage the walls of the hole and hold the sleeve against displacement. This same result can be accomplished by

providing the periphery of the sleeve 33 with roughened surfaces as shown in Figure 5. Instead however of roughening the surface of the sleeve the latter may be 5 provided with flanges 35, as shown in Figures 7 and 8 having holes for the passage of screws by which it may be secured to the door. In all instances wherein the sleeve is used, the latter is threaded internally for the screw 36 which is preferably provided with a cup shaped end 36^a to engage ridges 37 on the cylinder 32 of the pin tumbler lock. The cylinder 32 is provided with flattened sides, and it is 10 these flattened sides that are provided with the ridges or ribs 37, which are engaged by the screws and when so engaged, the cylinder of the lock will be held in place against the possibility of any movement 15 whatsoever. The flattened sides of the cylinder may be parallel as in Figure 2, or they may be at an angle as shown in Figure 6, so that the distance between the flattened sides will be greater at the rear end 20 of the cylinder than at the section taken at the point engaged by the screw 7 thus making it more difficult to withdraw the cylinder from the door by violence exerted at the front of the cylinder. The cylinder 25 is of the ordinary pin tumbler type and carries a rotary plug 38 normally held against movement by the pin tumblers 39 and moved by a key, not shown, in the ordinary and well known manner.

35 The plug of the pin tumbler lock is provided at its inner end with a pin 40 which rests in a circumferential slot 41 in the sleeve 42 which is secured to the connecting bar 42^a. The connecting bar passes through 40 plate 31 and carries a hub 43 having a cam 44 which is connected at its free end with the pitman 28. The dog 27 is centrally pivoted to a stud on the plate 31 and is actuated to engage and disengage the roll 45 back by said pitman.

In some instances it is desirable to use a smaller lock and locate the pin tumbler lock farther away from the edge of the door and such construction is shown in Figure 12.

50 In this latter construction the plate 31^a which corresponds to plate 31 of the construction shown in Figure 1, extends horizontally lengthwise the lower edge of the lock case instead of vertically, and the pitman 28 is horizontal instead of substantially vertical, thus shortening up the lock case to a considerable extent. This change in the 55 position of the pin tumbler lock is made possible by swinging the cam 44 and pitman 28 to the new position shown in Figure 12, and is also facilitated by the pin and slot connection 40-41 between the plug of the pin tumbler lock and the connection 42 between said plug and the outside lever handle,

which pin and slot connection also permits of a full revolution of the key plug to about an eighth of a revolution of the deadlocking cam 24, this lost motion of the pin in the slot permitting the plug to be revolved to a position where the key can be removed when the locking dog 27 is in its deadlocking position and also when turned to release the dog. This construction is simple and economical and permits of the necessary operation of the pin tumbler lock and dog which would not be possible without it.

70 With this construction the pin tumbler lock is supported by the door and not by the latch or lock casing consequently accuracy in boring the hole for the lock is not essential.

75 It is evident that many slight changes might be resorted to in the relative arrangement of parts shown and described without departing from the spirit of my invention within the scope of the appended claims and hence I would have it understood that I do not wish to confine myself 80 to the exact construction and arrangement of parts shown and described but,

85 I do not in this case claim the construction of bolt mechanism shown and described,—the same being comprehended by 90 my divisional application Serial No. 645,796.

Having fully described my invention what I claim as new and desire to secure by Letters Patent, is:

1. In means for securing a cylinder lock to a door independently of the lock casing, the combination with an internally threaded sleeve, means for securing said sleeve in a bore in the door, and a screw in said sleeve and adapted to engage the cylinder lock.

100 105 110 115 120 125 130

2. The combination with a door, of a cylinder lock located in said door, said door having a hole at an angle to the cylinder lock, an internally threaded sleeve in said hole, means whereby said sleeve is secured to the door, and a screw in said sleeve and engaging the cylinder lock to hold the same in place.

3. In a lock for automobile doors, the combination of a lock cylinder to be mounted in a hole in the door and having a flattened side, a sleeve secured in the door independently of any part of the lock casing and screw threaded internally and a clamping screw adjustable in the sleeve and bearing at its inner end on the flattened side of the lock cylinder for holding the latter in place and preventing it from turning.

130 135 140 145 150

4. In a lock for automobile doors, the combination of a cylinder to be mounted in the door and having a flattened and roughened face, a sleeve to be secured in the free edge of the door independently of the casing of the lock and threaded internally, and a screw mounted in said sleeve and adapted to bear

at its free end against the roughened flattened face of the cylinder.

5. In a lock for automobile doors, the combination of a lock cylinder to be mounted in a hole in the door, an internally threaded sleeve having a peripheral flange or enlargement provided with a roughened face, the said sleeve adapted to be forced into a hole in the edge of the door and held therein by friction, and a screw adjustable in said sleeve and adapted to bear at its inner end against the lock cylinder for holding the latter in place.

6. In a structure of the character described, the combination of a lock cylinder, a sleeve or bushing to be mounted in a bore in a part in which the lock cylinder may be located and having lateral projections to be embedded in the wall portion of said bore, said sleeve or bushing being threaded internally, and a set screw passing through said sleeve or bushing to engage the lock cylinder and secure the latter in place.

7. In a door lock, the combination of a cylinder the sides of which are flattened at an angle to the axis of the cylinder so that the diameter of cross section of the flattened sides will be greater at the rear end, a sleeve secured to the door and internally threaded and a screw mounted in said sleeve and adapted to be adjusted to engage a flattened side of the cylinder.

8. In a door lock, the combination of a cylinder the sides of which are flattened at an angle to the axis of the cylinder the flattened sides being roughened, a sleeve secured to the door and internally threaded and a screw mounted in said sleeve and adapted to be adjusted to engage a flattened and roughened side of the cylinder.

9. The combination with a door, of a lock cylinder in a seat therein and having a flattened scored face, and a screw carried by the door to engage said face of the cylinder and bind the latter against the opposite side of the seat in the door.

10. The combination with a door, of a lock cylinder mounted in a seat in the door and having a flattened scored face, and a securing screw mounted in the door and having a cup shaped end to engage the flattened scored face of the lock cylinder.

11. The combination with a door, of a lock cylinder in a seat therein, and a screw carried by the door to engage said cylinder and bind the latter against the opposite side of the seat in the door.

In testimony whereof, I have signed this specification in the presence of two subscribing witnesses.

PETER F. AUGENBRAUN.
